UNITED STATES PATENT OFFICE.

VERNON ROYLE, OF PATERSON, NEW JERSEY.

ATTACHMENT FOR ROUTERS.

No. 824,952.

Specification of Letters Patent.

Patented July 3, 1906.

Application filed December 30, 1904. Serial No. 238,942.

To all whom it may concern:

Be it known that I, VERNON ROYLE, a citizen of the United States, and a resident of Paterson, in the county of Passaic and State 5 of New Jersey, have invented a new and useful Attachment for Routers, of which the following is a specification.

My invention relates to an attachment for routers, and more particularly to an attachment for beveling the edges of a photo-engraving plate.

My invention contemplates clamping a plate-supporting plate to the table of a routing-machine and holding a plate to be beveled on said support in such position as to receive a beveling-cut from a cutter set in the chuck of the ordinary router-spindle.

A practical embodiment of my invention is represented in the accompanying drawings, 20 in which—

Figure 1 is a top plan view of a portion of the table of a routing-machine of any well-known or approved form, showing the plate-support clamped thereon in position for holding a plate to be beveled. Fig. 2 is a view in end elevation showing in vertical section the ordinary routing-spindle in its operative relation with respect to the plate-support. Fig. 3 is an enlarged view, in vertical section, showing the manner of holding the beveling-cutter in operative relation to the routing-tool. Fig. 4 is a view of the routing-tool in elevation, showing the recess for receiving the beveling-cutter. Fig. 5 is a bottom plan 35 view of the routing-tool. Fig. 6 is a top plan view of the beveling-cutter. Fig. 7 represents in top plan and longitudinal section the collar for holding the beveling-cutter to the routing-tool, and Fig. 8 is a top plan view of 40 the rotary guide.

The table of the router is denoted by 1. On the table 1 when the router is to be used for beveling purposes the bed plate or support 2 is clamped for the purpose of supporting and retaining the plate to be beveled in 45 position.

The support 2 is provided at its opposite ends with upwardly-extending ears 3 and 4, in which there is mounted a rock-shaft 5, carrying on its opposite ends, just inside the ears 3 and 4, levers, the hubs of which are denoted, respectively, by 6 and 7. The said levers are quite similar in their structure, each being provided with a rearwardly-extended arm 8

and a forwardly-extended arm 9, the forwardly-extending arms 9 of the levers supporting between their free ends a presser bar or clamp 10 for resting on the plate near the edge, where it is to be operated upon by the beveling-cutter to hold it firmly on the support 2.

The presser-bar 10 is secured between the arms 9 by means of screws 11 12, which will permit it to rock laterally to a sufficient extent to adjust its lower surface flatly to the top of the plate. The presser bar or clamp 10 is forced toward the support 2 by means of thumb-screws 13 14, seated in the support 2 with their upper ends bearing against the under sides of the outer ends of the arms 8 of the levers, and the lifting of the presser bar or clamp 10 from the plate to permit its removal or adjustment is provided for by a coil-spring 15, having one end fast to a collar 16, fixed on the rock-shaft 5, and its other end attached to a pin 17, set in the rear of the ear 3. The presser bar or clamp 10 carries a gage 18, consisting of a flat strip extending along the top of the bar 10 and projecting in front of it, as clearly shown, the said gage 18 being pivotally secured to the bar 10 by means of depending ears 19 20, made fast to the under side of the gage, through which screws 21 22 extend into screw-threaded sockets in the opposite ends of the bar 10.

The relation of the gage 18 and its supporting-ears to the bar 10 is such that when the gage is tilted over toward the front into an upright position (indicated in dotted lines, Fig. 2) its lower edge will indicate the line 90 along which the top of the bevel is to lie, and in adjusting the plate to the support 2 the plate is so manipulated that the lower edge of the gage 18 will indicate on it the line where the bevel is to terminate, and when 95 the plate has been clamped in this position by means of the levers which control the presser bar or clamp 10 the gage 18 may be thrown back into the horizontal position shown in full lines, Fig. 2, where its advance 100 edge serves the purpose of a track for guiding the beveling-cutter during its operation as follows: The spindle of the router is denoted by 23. In it there is a rod 24, operated by a hand-piece 25 and provided at its lower end with a screw-threaded portion 26, which engages the shank of the expanding and contracting check 27 for holding the router-tool 105

to the spindle. The routing-tool is denoted by 28, and while its cutting edge is left in its usual form for routing its face is provided with a recess or groove 29 for the reception of 5 the shank 30 of a beveling-cutter 31.

The beveling-cutter 31 consists, substantially, of an inclined blade projecting laterally from the shank 30, the said shank 30 being provided with a part immediately above 10 the blade 31 somewhat deeper than the recess or groove 29 and with a further upwardly-extending part 32 just the depth of the recess or groove 29, and when the said beveling-cutter is seated in the groove or recess 29 in the router it is held in position by 15 means of a collar 33, having a central opening 34, corresponding to the size and shape of the shank of the router, and with a recess 35, extending outwardly from the inner wall of the 20 opening 34 a distance sufficient to accommodate the deeper portion of the shank 30, located immediately above the cutting-blade, the said recess 35 being at its lower end extended through to the outer wall of the collar, 25 as shown at 36, Fig. 7, for embracing the upper part of the blade portion 31 of the beveling-cutter. The collar 33 is held in position on the router by means of a set-screw 37.

Between the collar 33 and the lower end of 30 the chuck 27 there is located a rotary disk 38, which is intended to travel with its periphery in contact with the forward edge of the gage 18, and as the support 2 is moved along with the table 1 to present the plate to the router 35 and beveler. The diameter of the guide-disk 38 is intended to correspond to the diameter of the circle in which the most extended portion of the cutting edge of the beveling-cutter travels, it being understood that 40 the cutting edge referred to in this statement is that part of the entire inclined edge of the cutter which actually engages the plate, and it is the intention to have a supply of guide-disks 38 of varying diameters at hand to suit 45 plates of different thicknesses or plates where

the bevel is to be at a greater or lesser distance from the line indicated by the gage 18.

In operation the router may cut its way not only along the edge of a plate to permit the beveling-cutter to operate throughout a 50 portion only of its rotary movement, but it may also cut its way through a plate, the beveling-cutter in this instance working on the plate throughout the entire or greater portion of its rotary movement. 55

The attachment as a whole is a comparatively simple one and because of its ready adjustment to the table of a router serves to supply with comparatively little additional expense an efficient beveling-machine, as well 60 as a router.

What I claim is—

1. The combination with the table of a routing-machine, of a plate-support removably secured thereto and provided with a 65 guide extending along its edge, a router-spindle, a beveling-cutter removably secured to the router-spindle and a removable roller mounted on the router-spindle above the beveling-cutter in position to engage the 70 guide at the edge of the plate-support.

2. The combination with the plate-support, a clamp for holding the plate to its support and means for adjusting the clamp toward and away from the support, of a cutter 75 movable along the plate-support, and a gage pivoted to the clamp and extending along the edge thereof, the said gage having a swinging movement over the edge of the clamp to determine the position of the plate and a swinging movement back into a horizontal plane to guide the cutter. 80

In testimony that I claim the foregoing as my invention I have signed my name, in presence of two witnesses, this 24th day of 85 December, 1904.

VERNON ROYLE.
